UNITED STATES PATENT OFFICE

ALBERT B. MAST, OF SHANESVILLE, OHIO

APPARATUS FOR GENERATING OIL GAS

Application filed December 28, 1929. Serial No. 417,192.

This invention relates to devices for generating fuel gas from fuel or crude oil, etc., for use particularly in internal combustion engines, although of course the device is not limited to such use for it may be used for generating gas for other purposes.

Another object of the invention is to provide an improved means for intimately combining the vapors of crude oil, fuel oil or gasoline with air whereby the same is delivered to the intake manifold of an internal combustion engine ready for use in the cylinders.

The invention broadly contemplates the provision of a receptacle adapted to contain a quantity of crude oil, fuel oil or the like, means being provided whereby an outlet of the receptacle may be connected directly with the intake manifold to enter the receptacle and caused to pass along a tortuous path through the oil therein before leaving through said outlet. Means is provided in the receptacle whereby the air and liquid will be intimately mixed and means is also provided for applying heat to the oil in the receptacle so that it will more readily volatilize and mix with the air passing therethrough.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a longitudinal sectional view through the device embodying the present invention showing the same connected with an engine intake and exhaust manifolds.

Figure 2 is a sectional view taken on the line 2—2 of Figure 1.

Figure 3 is a detailed vertical sectional view through the safety unit associated with the device.

Referring more particularly to the drawings wherein like numerals of reference indicate corresponding parts throughout the several views, the numeral 1 indicates generally the receptacle or casing of the oil gas generator embodying the present invention. In the lower portion of this casing, which as shown is of elongated rectangular design and relatively narrow in width, is formed a wall 2 which, being spaced from the casing bottom, forms a chamber 3 which is provided at one end with an inlet 4 and at the other end with an outlet 5. The inlet 4 of the chamber 3 is adapted to have connected thereto a suitable pipe 6 coupled to the exhaust manifold 7 of the engine in association with which the device is used so that the heated gases leaving the manifold will pass through this pipe and through the chamber 3.

The gas outlet 5 of the chamber 3 may open directly into the atmosphere or may have a muffler connected thereto as desired.

While the wall 2 forms the upper part of the heating chamber 3 it also forms the bottom of a gasifying chamber 8 in which the crude oil, fuel oil or gasoline which is to be volatilized and mixed with air for use in the engine is housed. At one end of the chamber 8 a vertical partition 9 is arranged which forms with the adjacent end wall 10 of the casing a relatively narrow air passage 11, which leads from the top of the casing to the lower partition wall 2. This end wall 10 has opening therethrough at the top of the casing an air inlet 12.

A section of the lower end of the wall 9 is in the form of a screen 13 which serves to break up air passing therethrough and leading from the upper edge of this plate longitudinally through the casing to a point adjacent the forward wall 14 is a second horizontal partition 15 which at its forward end connects with the lower edge of a second apertured wall or screen 16 which as shown is arranged in spaced relation to the forward wall of the casing.

Disposed horizontally above the second horizontal partition 15 is a third horizontal partition 17 which overlies the upper edge

of the screen 16, leading from the front wall 14 rearwardly to a point adjacent the vertical partition 9 where it joins a low upstanding plate 18 forming a tray in the upper part of the casing. There is thus formed by the partitions 9, 2, 15 and 17 an air passage through which air entering the casing through the opening 12 must pass in a tortuous path before reaching the outlet 19 which is in the top of the casing adjacent the forward end thereof as shown, the path followed by the air flowing through this tortuous path being indicated by arrows. It will also be seen that the air passing along this path also passes through both of the screens 13 and 16.

When in use the casing is filled through a suitable filling opening such for example as is indicated at 20 with the oil or gasoline to be used, the chamber 8 being filled to a level substantially in the plane of the top edge of the plate 18. Extending longitudinally of the casing and suspended between the front wall 14 and the top of the plate 18 is a shaft 21 upon which is rotatably mounted a plurality of radially slotted rotating disks 22, these disks preferably having the slots 10^a formed at an oblique angle to the faces thereof so that the air flowing up between the plate 18 and the partition 9 and longitudinally through the top of the casing 1 to the outlet 19 will cause a rotation thereof. The disks may also be so arranged that the air will be discharged through the slots of one disk in an opposite direction to the path of discharge through the adjacent disk so that opposite rotation of adjacent disks will be effected.

In order to further insure the satisfactory operation of the disks 22 by compelling all of the air to pass through the slits therein the upper part of the casing 1 may be rounded to conform to the curvature of the disks so that they will come into close proximity to the top wall of the casing.

The outlet 19 is controlled by a ball check 23 and this outlet has connected thereto a suitable hose 24 which at its other end is connected to the nipple 25 of a safety device 26. The device 26 is in the form of a small casing into which the nipple 25 opens, the inner end of this nipple being normally closed by a swinging or flap valve 27. An outlet pipe 28 leading from this casing is adapted to be coupled with the intake manifold 29 of an internal combustion engine.

In the lower part of the casing of the safety device 26 is a spring pressed check valve 30 which is designed to open outwardly only. It will be seen from the foregoing that in the event of a back fire in the intake manifold the pressure will be released through the outwardly opening check valve 30 of the safety device casing 26 and the burning gases will be prevented from getting into the casing 1 by the closing of the flap valve 27 and the ball check 23.

From the foregoing description it is thought that the operation of the oil gas generating device will be clear. The suction of the engine draws air into the intake 12 of the casing 1 down through the screens 13 and 16 and along the passage indicated and through the rotating disks 22 to the outlet 19 from where it passes through the valves 23 and 27 into the engine intake manifold. During this passage of the air through the oil or gasoline in the casing it will pick up or absorb the vapors and gases from the heated oil and thus enter the manifold as a mixture of oil, gas and air ready for burning. The vaporizing and gasification of the oil in the receptacle is made to progress more rapidly than it would under normal conditions by the heating thereof by the hot exhaust gases from the engine passing through the chamber 3 in the lower part of the casing.

While the drawings show the oil gas generator connected to the intake manifold of an internal combustion engine it is of course to be understood that I do not wish to be limited to the use of the same in this connection for it will be obvious that the generator may be advantageously employed in connection with burning devices such as stoves or the like in which case suitable means may be provided for forcing the air to circulate through the fuel liquid in the casing.

When, however, the device is used in association with an internal combustion engine it is used as an adjunct to the carburetor; the discharge of air and gas mixture from the generator being direct to the intake manifold of the engine in the manner shown.

Having thus described my invention, what I claim is:

1. An oil gas generator of the character described, comprising an elongated oil gas generating chamber having an air inlet in the upper part of one end wall and an oil gas outlet in the upper part and at the other end thereof, a vertical partition arranged adjacent the end wall through which the air inlet opens, a perforated member extending from the lower end of said partition to the bottom of the casing, a longitudinally extending partition leading from the upper part of said screen to a point adjacent the front of the casing, an upwardly extending perforated member projecting from the forward end of said longitudinal partition, a second longitudinal partition extending from the front wall of the casing over the upper edge of the second mentioned perforated member and terminating in an upwardly extending plate arranged in spaced relation with the vertical partition, a shaft extending longitudinally of the casing between the upper portion of said plate and the forward wall of the casing, a plurality of slotted disks rotatably mounted on said shaft, the casing being designed to contain volatile oil to a

level with the top of said plate, and means for conducting off oil gas from the upper part of the chamber.

2. An oil gas generator of the character described, comprising an elongated oil gas generating chamber having an air inlet in the upper part of one end wall and an oil gas outlet in the upper part and at the other end thereof, a vertical partition arranged adjacent the end wall through which the air inlet opens, a perforated member extending from the lower end of said partition to the bottom of the casing, a longitudinally extending partition leading from the upper part of said screen to a point adjacent the front of the casing, an upwardly extending perforated member projecting from the forward end of said longitudinal partition, a second longitudinal partition extending from the front wall of the casing over the upper edge of the second mentioned perforated member and terminating in an upwardly extending plate arranged in spaced relation with the vertical partition, a shaft extending longitudinally of the casing between the upper portion of said plate and the forward wall of the casing, a plurality of slotted disks rotatably mounted on said shaft, the casing being designed to contain volatile oil to a level with the top of said plate, means for conducting off oil gas from the upper part of the chamber, and a heating chamber disposed beneath the receptacle.

3. An oil gas generator of the character described, comprising an oil gas generating chamber having a gas outlet adjacent one end and passing through the top thereof, a tray like structure extending longitudinally of the upper portion of the chamber from the end adjacent the outlet to a point short of the opposite end forming an upwardly extending air passage between the tray and the said opposite end, a shaft extending longitudinally of said tray, a plurality of disks mounted upon said shaft to rotate therewith and having radial slots therethrough, the portions of the disks between the slots being arranged in the form of fan blades, a horizontally disposed longitudinally extending partition arranged in the chamber beneath said tray and extending from the said other end of the chamber to a point adjacent the first mentioned end, a screen covering the area between the bottom of said tray and the end of the partition adjacent the first mentioned end of the chamber, a screen covering the area between said partition and the bottom of the chamber adjacent the said other end thereof, means for passing air into the chamber through said last mentioned screen, and means for introducing oil into the chamber, said tray being filled with oil during the operation of the generator and

said disks being rotated by the passage of air through the slits therein.

In testimony whereof I hereunto affix my signature.
